UNITED STATES PATENT OFFICE.

VICTOR LIST AND JACOB KOSAKOFF, OF MOSCOW, RUSSIA, ASSIGNORS OF
ONE-HALF TO GEORG A. LIST, OF SAME PLACE.

PETROLEUM-MOTOR.

SPECIFICATION forming part of Letters Patent No. 371,849, dated October 18, 1887.

Application filed March 15, 1887. Serial No. 230,999. (No model.)

To all whom it may concern:

Be it known that we, VICTOR LIST, engineer, and JACOB KOSAKOFF, mechanic, both subjects of the Emperor of Russia, and residing at 5 Moscow, in the Russian Empire, have invented new and useful Improvements in Petroleum-Motors, whereof the following is a specification.

Our invention relates to engines in which motive power is produced by the explosive combustion of a mixture of vapors of liquid hydrocarbons—for instance, of petroleum—with air.

The improvements constituting the invention consist in the particular construction of the apparatus in which the said vapors are generated and mixed with air, (or carburetor;) in the means employed for varying the strength of the mixture; moreover, in the arrangement 20 of burners for combustible vapors that are produced within the same, the said burners serving on one hand to heat the carburetor at the beginning, and, on the other hand, to maintain the permanent flame from which fire is 25 transmitted to the explosive mixture, and in the construction of the device by which such transmission is caused, (or igniting device.)

On the annexed four sheets of drawings is represented a motor involving our improvements.

Figure 1 is a vertical section along the center line of the power-cylinder, some of the parts at the rear of the cylinder being omitted. Fig. 2 is a transverse sectional view; and Fig. 3, a plan, partly in section. Fig. 3^a is a part in detail. Fig. 4 is a longitudinal sectional view of the carburetor with a portion of the cylinders. Fig. 5 is a transverse section thereof on line y' z' of Fig. 4, and Fig. 6 a horizontal section. Figs. 7 and 8 are respectively a vertical and a horizontal section of the part of the engine containing the igniting device. Fig. 7^a shows the said device in a different position, and Fig. 7^b a part thereof. Figs. 4, 5, and 6 are drawn to a larger scale than Figs. 1, 2, and 3; Figs. 7, 7^a, and 8 to a still larger scale, and Fig. 7^b in about full size.

The motor comprises the main or power cylinder E and the compressing-cylinder B, 50 having pistons connected by rods to two cranks

placed on the same side of the shaft S, the said cylinders operating in like manner as the corresponding cylinders of the known gas-motors of similar construction. The cylinders communicate with each other by the channels m 55 and p and the valve-box C, in which is contained the valve n.

F is the exhaust-valve.

Both valves are acted upon by springs tending to keep them closed, and they are opened 60 at the proper moments by means of the shaft K, driven by bevel-wheels from the crank-shaft S, and provided with two tappets, a and t, the tappet a, Figs. 2 and 3, operating on the valve n through the roller a', rod g, and 65 bell-crank lever l, and the tappet t, Figs. 3 and 3^a, on the valve F through the roller u', rod u, and bell-crank lever v. The said rod g forms the piston of a small pump, J, the purpose of which will be explained hereinafter. 70 In order to facilitate the rotation of the fly-wheel by hand, required when the engine is to be started, the rod u is provided with another roller, u², which can be shifted lengthwise on its axle of rotation, and the shaft K with an- 75 other tappet, t', which has such position relatively to the tappet t that when the roller u² is pushed close to the rod u both tappets will act one after the other to keep the valve F open, the counter-pressure against the piston of the 80 cylinder E being thereby reduced or done away with. As soon as the engine is working, the roller u² is drawn back, so that then the rod u and the valve F are operated upon by the tappet t only.

Both cylinders E and B are inclosed in jackets, connected together by a pipe, u³, and the jacket of the cylinder E is supplied with cold water for the purpose of cooling the cylinder, while this water, after having become heated, 90 is conducted by the pipe u³ to the jacket of the cylinder B in view of transmitting heat to the same.

The carburetor A, (see especially Figs. 4, 5, and 6,) in which the vapors of petroleum are 95 produced and mixed with air, is composed of two parts. The first part consists in a box divided into three compartments, c, b, and d, and in a row of tubes, e, connecting together the outer compartments, c and d, and passing 100

- through the middle one, *b*. The tubes *e*, made of thin sheet metal, are lined with a material capable of imbibing petroleum or whatever other hydrocarbon is employed—for instance, 5 with hollow lamp-wicks. The compartment *c* is in communication with the surrounding air by the pipe *f*, and it is continuously supplied with petroleum by the pump *J* and the pipes *c* *c'* from the reservoir *Q*, arranged in 10 the frame of the engine. By means of the overflow-pipe *c'*, leading back to the reservoir *Q*, the petroleum in the compartment *c* is maintained at such a level that it may just pass into the tubes *e* and be sucked in by the wicks. 15 From the compartment *d* a pipe, *h*, provided with a self-closing valve, *i*, leads to the port *k* of the cylinder *B*. The said pipe extends upward beyond the level of the petroleum which passes through the tubes *e* into the compartment *d*, in order that the petroleum may be 20 prevented from running into the pipe. The middle compartment, *b*, finally is in communication with the jacket of the power-cylinder *E* by the valve-box *s* and the pipe *s'*, so that, 25 according as the valve in the box *s* is adjusted, more or less of the refrigerating-liquid, after having become heated, will circulate through the compartment *b* and heat the tubes *e*, petroleum being thereby evaporated. 30 Except in case light hydrocarbons are employed, it is advantageous to divide the inner space of the jacket into two portions, an upper one, *q*, and a lower one, *r*, the portion *q* being connected to the compartment *b* and 35 supplied with a liquid capable of being heated without inconvenience to a higher temperature than water—for instance, with oil—whereas the lower portion, *r*, may be fed with water, as usual in like machines. When the engine 40 is in operation and the carburetor is heated, as described, the piston of the compressing-cylinder *B* sucks in air through the pipe *f* and the tubes *e*. This air on passing through the tubes *e* mixes with the vapors generated 45 therein, while its temperature is raised; and the heated explosive mixture thus produced is thereupon drawn through the suction-pipe *h* and past the automatically-opening valve *i* into the cylinder *B*. 50 The second part of the carburetor consists in an apparatus arranged by the side of the first part and similar thereto, except that the tubes do not contain wicks and that it is not supplied with petroleum, the purpose of this 55 part being to heat air which is to be added to the explosive mixture in order to alter its strength. The said part is composed of the outer compartments, *c'* and *d'*, a middle compartment which is an extension of the de- 60 scribed compartment *b*, inasmuch as it is but partially separated therefrom by a wall, *b'*, and of the tubes *e'*, connecting together the compartments *c'* and *d'* and passing through the said extension of the compartment *b*. The 65 compartment *c'* is in communication with the outer air by the aperture *f'*, (shown in dotted

lines in Fig. 6,) and from the compartment *d'* leads downward a pipe, *h'*, which meets the aforesaid pipe *h* above the valve *i*. The portion of the middle compartment, *b*, traversed 70 by the tubes *e'* being filled alike to the portion containing the tubes *e* with hot liquor passing into the compartment from the cylinder *E* and circulating around the wall *b'*, (as shown by arrows in Fig. 6,) the air in the tubes 75 *e* will also become heated.

In the pipes *h* and *h'* are arranged the respective throttle-valves *h*² and *h*³, keyed at a right angle to each other on a common axle, *h*⁴, connected to the governor *M*, Figs. 2 and 80 3, the parts being so arranged that when the speed of the engine decreases and the balls of the governor approach each other the valve *h*² will increase the free area of the passage through the pipe *h*, whereas the valve *h*³ diminishes the area of the passage through the pipe *h'*, a greater amount of explosive mixture formed in the tubes *e'* and a smaller amount of air heated in the tubes *e* being then admitted to the cylinder *B*. Upon an increase 85 of speed of the engine occurring, the valves operate to diminish the strength of the mixture by admitting less thereof and more air. The vapors of petroleum which, during the pauses between the strokes of the engine, rise 90 in the pipe *f* condense on the walls of the pipe, and are thus prevented from passing into the engine-room.

The burners for combustible vapors that are produced within the same consist in a pipe 95 leading downward from a reservoir containing petroleum or other suitable hydrocarbon and inclosing in its lower portion, the end whereof is perforated, a wick or other material through which the petroleum, &c., may slowly percolate. Moreover, a metallic conductor of heat is fixed to the pipe close to the perforation or 100 perforations thereof.

The burner of this description serving to heat the carburetor at the beginning—*i. e.*, 110 before the engine is set in motion—is shown in Figs. 1 and 4. The same is composed of the pipe *x*, connected at its upper end to the reservoir *P* and having a cock, *x'*, of the horizontal pipe *y*, connected to the pipe *x* and 115 perforated at one side, and of the heat-conductor *w*, forming a flat tube open at both ends and fixed with its upper projecting side to the top of the pipe *y*, so as to be with one of its open ends opposite to the perforations of the 120 pipe. Into the lower part of the pipe *x* is inserted a wick, (which is not shown, but is in similar to the wick *w'*, shown in Fig. 7) or its aforesaid equivalent, and in front of the perforations of the pipe *y* is arranged a small gutter, 125 *z*; designed to contain asbestos. When with this arrangement some petroleum is allowed to pass by means of the cock *x'* to the asbestos and the same is lighted, the tube *w* will transmit the heat of the flame to the pipe *x* and 130 evaporate the petroleum contained in the wick which is inclosed in the said pipe. These va-

pors, while preventing by their pressure a too rapid flow of petroleum in the pipe x , pass out from the pipe y by the perforations thereof and burn with a strong clear flame under the compartment b of the carburetor, (the bottom whereof is preferably made of sheet-copper,) and thus heat the said compartment, together with its contents, and as the flame passes through the tube w heat is also transmitted from the same by this tube to the pipe x and a continuous production of vapors of petroleum is brought about for feeding the flame. In view of localizing the heat of the flame a kind of fire-box having a chimney, q' , 15 is arranged under the carburetor. After the carburetor has been heated in the described manner, the engine is set in motion, and as soon as the oil in the jacket of the power-cylinder has assumed a sufficient temperature the 20 flame of the burner is extinguished by closing the cock x' .

The device for igniting the explosive charge of the power-cylinder is constructed as follows: Opposite to the admission-port p of the 25 cylinder is arranged a sleeve, G , within which rotates a solid cylinder, the said sleeve forming in the present case a bearing of the aforesaid shaft K and the solid cylinder being a portion of the latter. The sleeve or bearing 30 G has three orifices, i' , k' , and l' , Fig. 7, arranged in one transverse plane and being respectively at the top, at the side, and at the bottom of the sleeve, the orifice i' leading to the permanent igniting flames m' , m^2 , the orifice k' to the port of the valve-box C , which is 35 in open communication with the admission-port p of the power-cylinder E , (see also Figs. 3 and 8,) and the orifice l' to the outer air. In the plane of the said orifices the shaft K is 40 provided with a transverse perforation, o , having a lateral branch, and into this perforation and its branch is inserted the igniting-tube D , comprising an inner chamber, 2 , Fig. 7^b, closed at the outer end, and an annular chamber, 3 , 45 open at its outer end and communicating with the chamber 2 by small holes 4 . Moreover, the chamber 2 communicates by the channel 5 and the lateral channel 1 with the groove 6 , Fig. 7, extending peripherically along a 50 portion of the surface of the shaft K . The width of the passage from the channel 5 to the channel 1 may be regulated by a screw, and above the orifice i' of the sleeve G is arranged a chimney, W . When the shaft K is in the 55 position shown by Fig. 7^a, in which its perforation o registers at the top with the orifice i' and at the bottom with the orifice l' , while the channel 1 of the igniting-tube is in communication by the orifice k' and the valve-box C 60 with the admission-port p , a small portion of the explosive mixture being compressed at the time will pass into the chamber 2 of the igniting-tube, and thence through the holes 4 into the annular chamber 3 , where it expands. 65 Finally it ignites at the permanent flames m' , m^2 , and, on account of its having but little

pressure, it burns with a steady flame at the outer end of the chamber 3 . This flame or transmitting-flame continues to be fed with explosive mixture through the groove 6 until, 70 by the rotation of the shaft K in the direction of the arrow 8 , Fig. 7^a, the end 7 of the groove 6 passes away over the orifice k' , and communication between the groove and the orifice is cut off. A little before this the orifices i' and 75 l' have been closed by the full parts of the shaft K . Immediately after the stoppage of the feeding of the transmitting flame, the upper end of the perforation o of the shaft K is brought in communication with the orifice k' , 80 and consequently with the valve-box C and the port p , so that the explosive mixture contained in the said box and the power cylinder is then ignited by the transmitting-flame.

The burner for the permanent flames m' , m^2 , 85 which is constructed similarly to the burner for heating the carburetor, consists of the pipe n' , Fig. 7, containing in its lower portion a wick, n^2 , or other material of the character stated above, and communicating with a reservoir for petroleum or other hydrocarbon, (not shown in the drawings,) which is placed at a higher level. Near the apertures for the egress of the vapors by which the flames are to be fed the metal tongues c' are fixed to the 95 pipe n' in such position that the flames will impinge upon them. The heat of the flames is thus utilized in this case also for converting the petroleum slowly running down through the wick into vapors, which thereupon pass 100 out through the said apertures. Previous to its employment the burner has to be withdrawn from the chimney W and heated by means of a lamp or otherwise until vapors are first produced. The purpose of the arrangement of two permanent flames is solely to obviate the danger of their being extinguished accidentally.

It remains to be observed that the improvements constituting our invention are not dependent upon the particular construction of engine shown by the drawings, and that they may as well be applied to other motors deriving their power from the combustion of explosive mixture—for instance, to the engines 110 of this kind in which the operations of drawing in the mixture and compressing it are carried out in the same cylinder in which the mixture is caused to produce mechanical work by its combustion.

We claim as our invention—

1. In a petroleum-engine, the combination, with a box having the compartment c , communicating with the outer air, and the compartments b and d , of the tubes e , lined with a material adapted to imbibe liquid hydrocarbons, suction-pipe h , pipe c' , for supplying hydrocarbon, and means for causing a heated liquid to circulate through the compartment b , substantially as and for the purpose specified. 125

2. In a petroleum-engine, the combination, with a box having the compartments c and c' ,

communicating with the outer air, and the compartments *b*, *d*, and *d'*, of the tubes *e*, lined with a material adapted to imbibe liquid hydrocarbons, tubes *e'*, suction-pipes *h* and *h'*, 5 pipe *c'*, for supplying hydrocarbon, and means for causing a heated liquid to circulate through the compartment *b*, substantially as and for the purpose described.

3. In a petroleum-engine, the combination, 10 with a box having the compartments *c* and *c'*, communicating with the outer air, and the compartments *b*, *d*, and *d'*, of the tubes *e*, lined with a material adapted to imbibe liquid hydrocarbons, tubes *e'*, suction-pipes *h* and *h'*, 15 throttle-valves *h'* and *h''*, fixed at a right angle to each other on the axle *h'*, governor *M*, means of connection between the axle *h'* and the governor, hydrocarbon-supply pipe *c'*, and means for causing a heated liquid to circulate through 20 the compartment *b*, substantially as and for the purpose specified.

4. In a petroleum-engine, the combination of the carburetor having the compartment *c*, 25 communicating with the outer air, the compartments *b* and *d*, the tubes *e*, lined as specified, the suction-pipe *h*, and the hydrocarbon-supply pipe *c'*, with the power-cylinder *E*, having a jacket, and means of communication between the said jacket and the compartment *b*, 30 substantially as and for the purpose described.

5. In a petroleum-engine, the combination of the carburetor having the compartment *c*, 35 communicating with the outer air, the compartments *b* and *d*, the tubes *e*, lined as specified, the suction-pipe *h*, and the hydrocarbon-

supply pipe *c'*, with the power-cylinder *E*, having a jacket divided into two portions, *q* and *r*, and means of communication between the jacket portion *q* and the compartment *b*, substantially as and for the purpose set forth. 40

6. In a petroleum-engine, the combination, with a reservoir for containing fluid hydrocarbon, of a pipe having perforations for the escape of the vapor, a porous substance contained within said pipe and through which the 45 hydrocarbon may percolate slowly, and a metallic heat-conductor against which the ignited vapor impinges, said conductor having contact with the pipe, whereby the hydrocarbon therein is vaporized, substantially as set 50 forth.

7. In a petroleum-engine, the combination, with the power-cylinder *E*, of the sleeve *G*, having the orifices *i*', *k*', and *l*', a burner for the permanent flame, the rotating cylinder *K*, having the perforation *o* and channel *6*, and the igniting tube *D*, containing the channels 1 and 5, and the chambers 2 and 3, communicating together by the holes 4, substantially as hereinbefore described, and for the purpose set 55 forth.

In testimony whereof we have hereunto set our hands in the presence of two subscribing witnesses.

VICTOR LIST.
JACOB KOSAKOFF.
